Primary Examiner — Mark A Goodwin(74) *Attorney, Agent, or Firm* — Boyle Fredrickson, S.C.(57) **CLAIM**

The ornamental design for a cover plate, substantially as shown and described.

DESCRIPTION

FIG. 1 is a front, raised perspective view of a cover plate according to a first embodiment of the invention; FIG. 2 is a front view of the cover plate of FIG. 1; FIG. 3 is a rear view of the cover plate of FIG. 1; FIG. 4 is a right side view of the cover plate of FIG. 1; FIG. 5 is a left side view of the cover plate of FIG. 1; FIG. 6 is a top view of the cover plate of FIG. 1; FIG. 7 is a bottom view of the cover plate of FIG. 1; FIG. 8 is a front, raised perspective view of a cover plate according to a second embodiment of the invention; FIG. 9 is a front view of the cover plate of FIG. 8; FIG. 10 is a rear view of the cover plate of FIG. 8; FIG. 11 is a right side view of the cover plate of FIG. 8; FIG. 12 is a left side view of the cover plate of FIG. 8; FIG. 13 is a top view of the cover plate of FIG. 8; and, FIG. 14 is a bottom view of the cover plate of FIG. 8. The surface shading illustrated in the drawings is provided merely to highlight the contour of the design and is not part of the claimed design.
